Primary Examiner — Ricky Pham

(74) Attorney, Agent, or Firm — Eversheds Sutherland (US) LLP

(57) **CLAIM**

The ornamental design for a feeding spoon for children, as shown and described.

DESCRIPTION

FIG. 1 is a perspective view of a feeding spoon for children showing our new design;

FIG. 2 is a top view of the feeding spoon for children of FIG. 1;

FIG. 3 is a bottom view of the feeding spoon for children of FIG. 1;

FIG. 4 is a left side view of the feeding spoon for children of FIG. 1;

FIG. 5 is a right side view of the feeding spoon for children of FIG. 1;

FIG. 6 is a front view of the feeding spoon for children of FIG. 1; and,

FIG. 7 is a rear view of the feeding spoon for children of FIG. 1.

The broken lines in the figures illustrate the portions of the design that form no part of the claimed design.

1 Claim, 5 Drawing Sheets
